UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

MECHANISM FOR OPERATING DUMP-CARS.

1,002,994.

Specification of Letters Patent. Patented Sept. 12, 1911.

Application filed September 14, 1907. Serial No. 392,878.

To all whom it may concern:

Be it known that I, FRANK S. INGOLDSBY, a citizen of the United States, residing at St. Louis, State of Missouri, have invented 5 a certain new and useful Improvement in Mechanism for Operating Dump-Cars, of which the following is a full, clear, and exact description, reference being had to the accompanying drawings.

10 The object of this invention is to provide simple and effective mechanism for automatically operating dump cars when they reach a desired point on the track.

15 The device is particularly valuable where a car is being used to carry material from a loading point out onto a trestle, thus saving one man at the unloading point.

20 The invention is adaptable to either cars propelled by a locomotive or by endless cable. An instance in the latter case where it is especially useful is where waste product from a mill is being carried to a dump.

25 The invention is well adapted for application to cars of the Ingoldsby type, where-in there is a central longitudinal member to which are hinged dumping doors which swing downwardly at their outer edges to discharge the load. With such cars the automatic devices may be arranged to dump 30 the entire car at one place or half of it may be dumped at one point and the remainder at another.

35 The invention is hereinafter more fully described and its essential characteristics set out in the claims.

The drawings illustrate my invention as applied to an Ingoldsby car. Figure 1 is a side elevation of half of such car. Fig. 2 is an enlarged cross section of a car, the 40 right hand half of this figure being in a plane indicated by the line A—A of Fig. 1, while the left hand half is in a plane nearer the center of the car, as indicated by the line B—B.

45 Referring to the drawings by reference numerals, 9 represents the side of the car; 10 the inclined end floor; 11 the central longitudinal member, which is shown as ridge shaped; 12 the load-supporting and dumping doors; 13 the floor beams which carry these doors and which are pivoted to the central member; 15 the hooks carried by the sides of the car for engaging and supporting the floor beams. This much of the 55 construction is usual in Ingoldsby cars,

wherein there is also a pivoted operating lever connected by links with the hooks 15.

In the present car, instead of the usual operating lever, I provide a lever 20 pivoted at 21 to the car side and extending both 60 upwardly and downwardly from its pivot, and above its pivot connected by links 16 and 17 with the hooks 15. Below its pivot this lever 20 is provided with a hooked catch 22 which normally engages a gravity 65 latch 23 pivoted at 24 to the car side. Pivoted at 25 to the car side, or to means carried thereby, and below the latch 23 is a freely depending operating lever. This lever has a long arm 26 and a short arm 27 projecting at an angle thereto and adapted to raise the latch when this lever is operated.

70 Located at a point along the track where it is desired to effect the dumping is a suitable bumper 30 which is shown as a peak 75 or inverted-V secured to the ties. This bumper lies directly in the path of the long arm 26 of the pendulum lever. When the car moving along the track, in the direction of the arrow in Fig. 1, comes to the dumping point, the arm 26 engages the bumper 30 and is swung thereby toward the end of the car. This movement causes the short arm 27 to engage a lug 28 on the latch 23 raising that latch to release the lever 20. 80 Coincident with this release or shortly thereafter the lower end of the lever 20 engages the bumper and is swung thereby toward the end of the car, thereby swinging the hooks 15 to release the floor beams and 85 thus dumping the car. This dumping position of the parts is illustrated by dotted lines in Fig. 1. To insure the lever 20 returning idly over the bumper 30, I provide its upper end with a counterweight 29 90 which gives it a slight movement in addition to that given by the bumper when it is released, thus causing it to certainly clear the bumper on the return movement. The lever 26 does engage the bumper on the return movement but simply swings idly in 95 reverse direction.

100 The bumpers 30, as shown, are flat straps bent into an inverted V form and having laterally projecting ends which are spiked 105 to the ties 8. The bumpers may be opposite on the two sides of the track or located at different points according to where it is desired to dump the car. To insure the bumpers being properly placed laterally so 110

as to be in the path of levers 26 and 20, I arrange the inner edge of the bumper to engage the base of the rail 7.

It will be seen that this mechanism is 5 very simple in construction, and does not interfere with the ordinary dumping of the car by hand whenever desired.

The bumpers may be located at any point 10 along the track and may be conveniently moved from place to place as frequently as required.

Having described my invention, I claim:

1. The combination of a dump car having a dumping door and depending operating lever, and means located adjacent to the track for unlocking and moving said lever.

2. The combination of a dump car having outwardly discharging doors, supporting hooks and a depending operating lever, and 20 means located adjacent to the track for unlocking and moving said lever.

3. The combination with a dump car having a dumping door, supporting mechanism, an operating lever for said mechanism, a latch for the operating lever, and mechanism adapted to be engaged by a stationary projection for operating said latch and lever.

4. The combination with a dump car having a dumping door, supporting hooks on 30 the side of the car, an operating lever linked to said hooks, a latch for the operating lever, and mechanism adapted to be engaged by a stationary projection for operating said latch and lever.

5. In a dump car, the combination of a 40 load-supporting door, of supporting and releasing mechanism, a lever for operating the same, a gravity latch for restraining said lever, and a depending lever for operating said latch.

6. In a dump car, the combination of a release lever, a latch for restraining it, a lever for releasing the latch, and means carried independently of the car and adapted 45 to be engaged by both levers.

7. In a dump car, the combination of a 50 lever, releasing mechanism operated thereby, a gravity latch for restraining said lever, a pendulum lever for operating said latch, and a bumper located along the track-way in position to engage the pendulum lever and releasing lever.

8. The combination of a dump car, a lever for releasing it to cause the dumping, means independently of the car standing normally in the path of said lever and adapted to operate it, and means for giving said lever an additional movement.

60 9. The combination of a car having a central longitudinal beam and doors hinged thereto, depending releasing levers for the doors, one of which may unlatch the other, and a dumper adapted to be engaged by said levers and thereby operate them.

10. The combination of a side dumping dump car, a releasing member at the side of the car, a latch for restraining the releasing member, a lever for operating the latch to free the releasing member, and controlling means located in the path of said lever.

70 11. The combination of a side dumping dump car, a releasing lever pivoted at the side of the car and depending, a latch for restraining the releasing lever, a lever for operating the latch to free the releasing lever, and a bumper located in the path of both levers.

75 12. In a dump car, the combination of a central longitudinal member, doors hinged thereto and adapted to swing downwardly at their outer edges, supporting hooks pivoted at the sides of the car and adapted to support said doors, levers pivoted to the sides of the car and connected with said hooks 80 for operating them to release the doors, latches for engaging said levers, pendulum levers having short arms adapted to engage said latches and long depending arms extending in front of the releasing levers, and means adapted to be secured to the track-way and stand in the path of said long arms and said levers.

90 13. In a dump car, the combination of a longitudinal member, a door hinged thereto and adapted to swing downwardly at its outer edge, supporting hooks pivoted at the side of the car and adapted to support said door, a lever pivoted at the side of the car and connected with said hooks for operating them to release the door, a catch formed on 95 said lever, a gravity latch for engaging said catch, a pendulum lever having a short arm adapted to engage said latch and a long depending arm extending in front of the releasing lever, and a bumper adapted to be secured to the track-way and stand in the path of said long arm and said lever.

100 14. In a dump car, the combination of a central longitudinal member, doors hinged thereto and adapted to swing downwardly at their outer edges, supporting hooks pivoted at the sides of the car and adapted to support said doors, levers pivoted at the sides of the car and connected with said hooks, for operating them to release the doors, catches formed on 110 said levers, gravity latches for engaging said catches, pendulum levers having short arms adapted to engage said latches, and long depending arms extending in front of the releasing levers, bumpers adapted to be secured to the track-way and stand in the path of said long arms and said levers, said bumpers being flat straps bent into inverted V-shapes with 115 lateral projecting ends adapted to be secured to ties.

120 15. The combination of a dump car, a depending lever for releasing it to cause the dumping, means independent of the car 125

130

adapted to stand in the path of said lever and operate it, and a counterweight on the upper part of said lever.

16. The combination of a dump car, normally locked releasing mechanism, and a counterweight for holding such mechanism released after being once released.

17. The combination of a dump car, mechanism whereby a bumper along the trackway may initiate the discharge from the car, and means for automatically moving such mechanism out of the path of the bumper when the car is released.

18. The combination of a dump car, a releasing lever therefor, a latch for holding the releasing lever, and mechanism adapted to be operated by means located along the trackway for causing said latch to release the lever.

20 19. The combination of a normally locked car, a lever for releasing it, a latch for holding the lever in active position, and a bumper located along the trackway for causing the latch to be unlocked, said bumper thereafter moving the lever to release the car.

20 20. In a dump car, the combination of locking mechanism, a latch therefor, and a bumper located along the trackway and adapted to operate both the latch and the locking mechanism.

25 21. In a dump car, the combination of dumping doors, door supporting mechanism, a lever for operating the same to release the doors, and a bumper to first unlatch said lever and then operate it.

22. In a dump car, the combination of dumping doors, door supporting mecha-

nism, a lever for operating the same to release the doors, a bumper to operate said lever, a latch for holding said lever, said bumper also operating to release said latch.

23. The means for automatically dumping a dump car, having a normally latched locking mechanism comprising a bumper operating to release first the latch and then operate the locking mechanism.

24. In a dump car, the combination of locking mechanism, a latch, and means for first operating the latch and thereafter the locking mechanism.

25. The combination of a dump car, a depending lever for releasing the same, a counterweight formed on said lever tending to hold it to idle position when there placed, and a latch for holding said lever in active position.

26. In a dump car, the combination with a load supporting door and pivoted supporting hooks on the car side, of a lever pivoted on the side and connected with said hooks, a counterweight tending to hold said lever in released position when swung into that position, and a latch adapted to hold the lever in active position.

27. The combination of a dump car, normally locked releasing mechanism, a bumper for operating such mechanism, and a counterweight for holding the mechanism released after the bumper has acted.

In testimony whereof, I hereunto affix my signature in the presence of two witnesses.

FRANK S. INGOLDSBY.
